UNITED STATES PATENT OFFICE.

RICHARD E. MEYER, OF DETROIT, MICHIGAN.

EXPLOSIVE-ENGINE.

1,354,675.

Specification of Letters Patent.

Patented Oct. 5, 1920.

Application filed September 14, 1918. Serial No. 254,147.

To all whom it may concern:

Be it known that I, RICHARD E. MEYER, a citizen of the United States of America, residing at Detroit, in the county of Wayne 5 and State of Michigan, have invented certain new and useful Improvements in Explosive-Engines, of which the following is a specification, reference being had to the accompanying drawings.

10 In the operation of explosive engines of the sleeve valve type, or those using reciprocable or rotary split compression shells, sleeves or rings, it is essential that some means be employed at the split or separable edges of the sleeve or shell, to prevent the escape of compression from within the cylinder of the engine. In positively confining the compression within the cylinder of the engine, friction between the sleeve or shell and the piston or engine block is reduced to a minimum, and the efficiency of 20 the engine materially increased.

The primary object of my invention is to provide a novel packing member or members that may be readily located at the split or separable edges of a sleeve, shell or ring to afford one or more transverse partitions in the space that may exist between the confronting edges of the split sleeve. In certain forms of the packing or partition members, said members are fixed relative to one edge of the split sleeve and are movable in the opposite edge thereof, while in another form of the packing, the member or parts thereof possess resiliency and has an inherent tendency to constantly pack the variable space between the confronting edges of a split sleeve.

Another object of my invention is to provide simple and effective means for establishing a driving relation between a rotary cylinder, sleeve, shell or ring and operating mechanism therefor, and this feature of my invention may be considered as an improvement in connection with my prior Patent No. 1,188,297, of June 20, 1916, wherein there is disclosed a sleeve valve that has split interlocking edges and novel means of attaching said sleeve valve to a gear or driving device. The present invention may also be considered as an improvement in connection with my engine disclosed by my application Serial No. 91,564, filed April 17, 1916.

55 The present invention will be hereinafter

specifically described and then claimed, and reference will now be had to the drawings, wherein—

Figure 1 is a vertical sectional view of a portion of an engine, provided with one 60 form of packing member;

Fig. 2 is a similar view of a portion of the engine illustrating a modified form of the sleeve or cylinder connection with its 65 driving gear;

Fig. 3 is a horizontal sectional view of the same;

Fig. 4 is a perspective view of the lower 70 end of the sleeve or cylinder shown in Fig. 1;

Fig. 5 is a perspective view of a coupling ring adapted to establish a driving relation between a gear and the sleeve or cylinder;

Fig. 6 is a perspective view of a self-adjusting packing member;

Fig. 7 is a side elevation of a portion 75 thereof;

Fig. 8 is a horizontal sectional view of a portion of the sleeve or cylinder provided with the adjustable packing member;

Fig. 9 is a side elevation of a portion of a 80 split sleeve or cylinder showing another form of packing member;

Fig. 10 is a horizontal sectional view of the same;

Fig. 11 is a side elevation of a portion of a split sleeve or cylinder, showing a further 85 form of packing member;

Fig. 12 is a similar view illustrating a still further form of packing member;

Fig. 13 is a similar view illustrating a combination of packing members;

Fig. 14 is a perspective view of a portion of one of the packing members shown in Figs. 9 and 10;

Fig. 15 is a perspective view of one of the packing members shown in Fig. 12;

Fig. 16 is a perspective view of one of the packing members shown in Fig. 13; and

Fig. 17 is a similar view of one of the 100 packing members shown in Fig. 7.

An engine in accordance with my invention may include one or more cylinders, but for an understanding of the present invention there is shown a single cylinder or block 105 1 having the upper end thereof provided with opposed ports 2 communicating with the chambers 3, and below said chambers is a conventional form of water jacket 4. The upper end of the cylinder is closed by a head 110

5 and the lower end thereof is opened to communicate with a crank case 6. Rotatable in the cylinder 1 is a sleeve valve 7 which has the upper end thereof 5 ported, as at 8, to communicate with the ports 2 of the cylinder 1. The lower end of the sleeve valve extends out of the lower open end of the cylinder 1 and is provided with a horizontally disposed gear wheel or 10 circular rack having hub portions 10 and 11. The hub portion 10 extends into an annular recess 12 provided therefor in the lower end of the cylinder 1, and loosely surrounding the hub portion 11 of the gear 9 is a cap or 15 retaining ring 13 bolted or otherwise connected to the cylinder 1, as at 14. The cap or retaining ring 13 supports a coupling ring 15 provided with a plurality of radially disposed lugs 16 extending into notches or recesses 17 in the lower end of the sleeve valve 7 and notches or recesses 18 in the hub portion 11 of the gear 9. The coupling ring 15 therefore establishes a driving connection between the gear 9 and the lower end of the 20 sleeve valve, and as a modification of said driving connection, there is illustrated in Fig. 3, a sleeve valve 19 which has its lower end provided with a plurality of radially disposed set screws or projecting members 25 20. These set screws or projecting members are adapted to extend into radially disposed openings 21 in the hub portion 22 of a gear 23. The gear 23 is devoid of an upper hub portion, but has a lower hub portion 25 rounded by a cap or retaining ring 24 suitably connected to the cylinder of the engine. In either instance, the gear 9 or 23 meshes with a worm 24 operable in an offset portion 25 of the cylinder 1, said worm being 30 35 suitably driven from the main crank shaft of the engine.

The sleeve valve 7 has a longitudinal slit or slot in alignment with one of the ports 8 of the sleeve valve, said slit or slot permitting of expansion and contraction of said sleeve valve during rotation in the cylinder 1. For one form of packing the slit or slot has its confronting faces concaved, as at 27, and beveled, as at 28. The concaved wall 50 of the sleeve valve borders on the inner wall of said sleeve valve so as to form feather or knife edges 29 and the beveled faces 28 are at the outer wall of the sleeve valve and disposed to form a flared or inwardly tapered 55 entrance into the groove having for its walls the concaved walls 27 of the sleeve valve. By reference to Fig. 1, it will be observed that the concaved and beveled walls extend from a point in proximity to the port 8 to 60 a point set in some distance from the lower end of the sleeve valve and at the ends of the concaved and beveled wall there are transverse slots 30. These slots are adapted to receive heads 31 of a compressible and 65 expandible packing member 32. The mem-

ber 32, as best shown in Figs. 6 and 8 is substantially semi-cylindrical and has its longitudinal edges flared to provide outwardly or angularly disposed flanges 33.

The ends of the member 32 intermediate the sides edges thereof, have necks 34 welded or otherwise fixed to the heads 31, as shown in Figs. 6 and 7, so that while the heads 31 hold the member between the confronting faces of the split sleeve valve yet the side walls of said packing member may be distended or retracted as the sleeve valve expands and contracts during the operation of the engine. The semi-cylindrical portion of the packing member is adapted to engage the concaved walls 27 of the sleeve valve and by engaging the feather or knife edges 29 seal any gap that exists between the feather edges of the sleeve valve. The more that the sleeve valve contracts, the closer the feather edges are brought together, the greater will be the sealing power of the packing member 32, since said member will be crowded between the confronting faces of the sleeve valve. As said valve tends to expand, the flanges 33, which are normally out of engagement with the beveled faces 28 contact with said beveled faces and the resiliency of said packing member is sufficient to maintain the semi-cylindrical portion of the packing member constantly against the concaved wall 27 of said sleeve valve, and thus pack the gap or space between the confronting faces of the sleeve valve. The feather or knife edges 29 of the valve will be wiped by a piston 35 reciprocable in the sleeve valve, and with said sleeve valve under its maximum or minimum expansion, the piston contacts with the packing member 32, and there is no danger of the compression within the sleeve valve escaping past the piston.

Reference will now be had to Figs. 9, 10 and 14 showing another form of packing member. A sleeve valve 26 is slotted or slotted similar to the sleeve valve 7 and the confronting faces of the split sleeve valve are provided with opposed transverse and equally spaced slots 36 adapted to receive blades 37 carried by one or more members 38, said members and the blades 37 being cut, stamped or pressed from sheet metal with the blades disposed substantially at right angles to the members 38. The blades 37 are positively held at an angle to the members 38 by portions 39 thereof, and to hold the member 38 in position relative to the split sleeve valve, said sleeve valve has a seat 40. The member 38 may be countersunk and fixed in the seat 40 by screws 41 or other fastening means, thus positioning the member flush with the periphery of the sleeve valve and there is no danger of the walls of the cylinder 1 being scored or injured by the packing member during the rotation of the sleeve valve in its cylinder 130

The blades 37 of the packing member constitute a plurality of partitions that extend crosswise of the split portion of the sleeve valve and prevents the travel of compression lengthwise of the sleeve valve. The compression is therefore confined between the blades 37 should a gap or space exist between the confronting faces of the split sleeve valve.

- 10 The form of packing member shown in Figs. 11 and 17 consist of a plurality of independent or single blades or partitions 42 that are placed in opposed slots 43 in the confronting faces of a split sleeve valve 44.
- 15 It is preferable to fix the ends of the blades or partitions 42 in the slots 43 in one face of the sleeve valve 44, and allow the opposite ends of the blades or partitions to extend into and slide in the slots 43 in the 20 other face of the split sleeve valve, during the expansion and contraction of said sleeve valve. The blades or partitions 42 may be perfectly fitted, as to size for the slots 43 in which they are to be fixed and the fixing 25 may be accomplished by brazing or using some suitable securing means. For instance, as shown in Figs. 12 and 15, the ends of the blades or partitions may have apertured lugs 45 seated or countersunk in the periphery of a sleeve valve 47 and screws or 30 other fastening means 48 may be employed for securing the lugs to the sleeve valve.

A combination of the packing members is shown in Fig. 13, the combination consisting of spaced blades or partitions 49 and short lengths of packing members 50 similar to the member 32. The blades or partitions will positively prevent compression from traveling lengthwise of a sleeve valve 40 51 in which the combination of packing members are placed, and the short packing members 50 operate similar to the long member 32.

To insure easy rotation of the sleeve valve 45 in the engine cylinder, each sleeve valve has its periphery provided with spiral grooves or lubricant ways, 52, the spiral formation of which is interrupted at the split of the sleeve valve, but during the rotation of the 50 valve in either direction, with the grooves accordingly disposed, the grooves pick up or receive a lubricant from one another. The main supply groove is circumferential of the sleeve valve and is designated 53, said 55 groove communicating with a port 54 in the cylinder 1 through which the lubricant may be forcibly fed. To lubricate that portion of the sleeve valve in proximity to the port 8 or the upper end of the sleeve valve there 60 are angularly disposed grooves 55 and lubricant is supplied to these grooves, from the grooves 52 during rotation of the sleeve. The lubrication of the sleeve is facilitated, particularly in connection with the construction shown in Figs. 9, 10 and 14 since the 65

spaces designated 39^a afford lubricant pockets, said spaces being practically throughout the length of the sleeve valve. While referring to these figures, particularly Fig. 9, wherein a piston with piston rings is shown in the sleeve valve, it will be noted that the space of the blades 37 is such that one or more of the piston rings are bound to seal the piston relative to the sleeve valve. In other words there is always one or more piston rings between the blades during the reciprocation of the piston within the sleeve valve.

I am aware of sleeve valves having interlocking edges, but the majority of such edges prohibit the turning down or machining of the valves for perfect fitting in a cylinder, whereas, the edges of my sleeve valve do not interfere with any machine work on the sleeve valve, since the edges are devoid of tongues and practically uninterrupted.

It is thought that the operation and utility of the sleeve valves in accordance with my invention may be apparent without further description, and while in the drawings there are illustrated the preferred embodiment of my invention, it is to be understood that the structural elements are susceptible to such variations and modifications as fall within the scope of the appended claims.

What I claim is:—

1. The combination with an engine cylinder, a split sleeve valve rotatable therein, a reciprocable piston in said sleeve valve, and means adapted to operate said valve and piston in timed relation, of blades set in the confronting faces of said split sleeve valve, and a compressible packing member between said blades and the faces of said split sleeve valve.

2. The combination with an engine cylinder, of a rotatable sleeve valve therein and adapted to have a piston reciprocated therein, said sleeve valve having a longitudinal slit providing confronting faces, transverse blades set in the confronting faces of said sleeve valve, and a compressible packing member extending from one blade to the other and constantly engaging the confronting faces in the split of said sleeve valve.

3. The combination of an engine cylinder, a sleeve valve rotatable therein adapted to have a piston reciprocated therein, blades in one face of the split sleeve valve and extending transversely of the split into the other face of the sleeve valve, and means connecting said blades and constantly engaging the faces in the split of said sleeve valve.

4. The combination with an engine cylinder, of a rotatable sleeve valve therein adapted to have a piston reciprocated therein, said sleeve valve having its lower end

- notched, a gear at the lower end of said sleeve valve adapted to impart movement thereto, said gear having a lower notched hub portion with the notches thereof registering with the notches of said sleeve valve and means extending into the notches of said sleeve valve and the hub portion of said gear establishing a driving relation between the said sleeve valve and notched portion of said gear.
5. The combination of a split sleeve, and a compressible packing member in the split of said sleeve and having its ends anchored relative to said sleeve.
- 15 6. The combination of a sleeve having a split, and a semi-cylindrical packing member having sides thereof seated on the faces of the split of said sleeve.
7. The combination of a sleeve having a split presenting concave faces, and a semi-cylindrical packing member having its ends anchored relative to said sleeve and its sides seated on the concave faces of said split sleeve.
- 25 8. The combination of a sleeve having a split presenting concave faces, a compressible member in the split of said sleeve engaging the concave faces thereof, and means at the ends of said faces supporting said compressible member.
9. A sleeve valve comprising a sleeve having a split presenting feather edges, and a compressible member between the edges of said split sleeve which tends to more firmly engage the edges of said split sleeve 35 by contraction of said sleeve.
10. A sleeve valve comprising a sleeve having a split presenting concave faces with feather edges, a compressible member constantly engaging the concave faces of 40 said split sleeve and closing the gap between the feather edges of said concave faces, and means transversely of the split of said sleeve supporting said compressible member relative to said sleeve. 45
11. A sleeve valve comprising a sleeve having a split presenting feather edges, and a hollow semi-cylindrical compressible member in the split of said sleeve adapted to be crowded therein to seal the gap between the feather edges of said sleeve. 50
12. As a new article of manufacture, a hollow semi-cylindrical compressible member having blades fixed at the ends thereof so that the sides of said member may yield 55 independently of said blades.
- In testimony whereof I affix my signature in the presence of two witnesses.
